UNITED STATES PATENT OFFICE.

JOHN S. BRISTOL, OF DANBURY, CONNECTICUT.

DRIVING BIT.

Application filed December 16, 1926. Serial No. 155,214.

This invention relates to driving bits and particularly to an improved bit for race horses and has for an object to provide a construction which will be easy on the mouth of the horse and at the same time present means for closing the parts to keep a straight line.

Another object of the invention is to provide an improved bit for race horses wherein means have been provided which will permit the driver to prevent any side movement or deviation from a proper course while guiding the horse in the usual manner.

In the accompanying drawing—

Figure 1 is a front view of a bit disclosing an embodiment of the invention.

Figure 2 is a top plan view of the structure shown in Figure 1.

Referring to the accompanying drawing by numerals, 1 indicates a plate which is flat and provided with comparatively large openings 2 and 3 adjacent the ends. Eye members 4 and 5 extend through the openings 2 and 3 loosely so that the bars 6 and 7 may freely swing. This construction permits the plate 1 to lie flat on the tongue of the horse and also permits the horse to force his tongue beneath the plate by reason of the fact that the plate is held up slightly by the eye members 4 and 5. The bars 6 and 7 merge into journal members 8 and 9 which in turn merge into what may be termed siding members 10 and 11 adapted to prevent siding of the horse or a movement to one side. An aperture extends through each of the journal members 8 and 9, said apertures accommodating the pintle portions 12 and 13 of the vertical rods 14 and 15. These vertical rods at their upper ends are provided with loops or eye members 16 and 17 for receiving part of the bridle straps while at the lower part rings 18 and 19 are formed,

preferably integral with the rods 14 and 15, said rings 18 and 19 being adapted to receive the straps or rings 20 and 21.

When the bit is in use, the rings 18 and 19 are positioned approximately as indicated in dotted lines in Figure 2 and in order to hold the horse in the desired course, the reins are pulled comparatively tight which will swing the bars 6 and 7 so that the members 10 and 11 will press against the side of the head adjacent the mouth of the animal. Any slight additional strain will press these members into the animal's head and, consequently, prevent any side movement so that there is no loss of time by a side movement or a movement out of a straight course.

What I claim is:

1. A bit used in driving race horses comprising a flat centrally positioned plate, a pair of bars loosely pivotally connected with the plate, a siding ear connected with each of said bars, a ring pivotally mounted on each of said bars and adapted to be connected to the reins of the bridle, and means connected with each of the rings for securing the bridle to the overhead strap of the bridle.

2. A driving bit for bridles comprising a central plate having a comparatively large aperture at each end, a bar at each end of the plate having an eye member looped through the aperture but only partly filling the same whereby a very loose pivotal connection is provided, each of said bars having formed integral therewith a siding ear extending at less than a right angle from the respective bars, and a ring pivotally mounted on each of said bars at the juncture of the ears with the bars.
